UNITED STATES PATENT OFFICE.

IRVING F. BYRNES, OF SCHENECTADY, NEW YORK, ASSIGNOR TO GENERAL ELECTRIC COMPANY, A CORPORATION OF NEW YORK.

AMPLIFIER.

Application filed November 1, 1924. Serial No. 747,385.

My present invention relates to systems for amplifying small variable currents, such for example, as those produced in response to sound waves, and more particularly to 5 means for controlling the amount of amplification produced by an amplifying system.

In the amplification of telephone currents, particularly where the amplified currents are to be employed for modulation of high 10 frequency currents, it is desirable to have means for controlling the amount of amplification which is obtained by the amplifying apparatus.

It is also desirable to control the amount 15 of amplification at frequent intervals during the rendition of a musical selection, or during the course of an address.

The object of my invention is to provide a means for controlling the amount of amplification at the will of the supervising operator without at the same time introducing 20 objectionable noises when the apparatus is being adjusted.

The novel features which I believe to be 25 characteristic of my invention are set forth with particularity in the appended claims. My invention itself, however, will best be understood by reference to the following description taken in connection with the accompanying drawing in which I have indicated 30 diagrammatically a circuit arrangement whereby my invention may be carried into effect.

I have indicated in the drawing an amplifying arrangement for amplifying the variable currents produced by means of a push-pull microphone 1. This microphone is connected in a circuit arrangement commonly known as a push-pull circuit. This 40 circuit includes a source of direct current 2, which is connected to one contact at the microphone 1 and to the central point of a primary winding 3 of a transformer, the terminals of which are connected to the other two contacts of the microphone 1. The transformer primary 3 supplies currents to a secondary winding 4, which is included in the grid circuit of a thermionic amplifier 5. The output or plate circuit of amplifiers 5 45 includes an output transformer 6 by means of which the amplified currents may be supplied to other amplifiers or to modulating devices, as desired.

In order to control the amount of amplification produced by amplifier 5 the primary

winding 3 is shunted by an impedance which in the present case I have indicated as an adjustable resistance 7. This resistance is connected between two points which are at the same potential with respect to the direct 60 current component of the source 2, and when the value of resistance 7 is adjusted no objectionable clicks will be produced in the circuit arrangement as would be the case if the resistance were connected between two 65 points which were at a different potential with respect to the direct current component of the source. By a variation of the resistance 7 current flowing in the transformer primary 3 may be varied at will and thereby 70 the current supplied from the output transformer 6 may be varied.

While I have shown and described only one specific embodiment of my invention it will be apparent that many modifications in 75 the circuit arrangement used and the form of apparatus employed may be made without departing from the scope of my invention as set forth in the appended claims.

What I claim as new and desire to secure 80 by Letters Patent of the United States, is:—

1. The combination in an amplifying system of a push-pull circuit arrangement which includes a source of direct current, and means for producing variable currents 85 from said source of direct current, and an impedance connected between two points in said circuit arrangement which are at the same potential with respect to the direct current component of the source but at different 90 potentials with respect to the variable currents.

2. The combination in an amplifying system of a push-pull circuit arrangement which includes a source of direct current 95 and means for producing variable currents from said source of direct current, and a variable resistance connected between two points in said circuit arrangement which are at the same potential with respect to the direct current component of the source but at different potentials with respect to the variable currents.

3. The combination in an amplifying system of a push-pull circuit arrangement 105 which includes a source of direct current and means for producing variable currents, a transformer primary included in said circuit arrangement by means of which variable currents may be supplied to another cir- 110

cuit, and an impedance connected between two points in said transformer primary which are at the same potential with respect to the direct current component of the source.

4. The combination in an amplifying system of a push-pull circuit arrangement which includes a source of direct current and means for producing variable currents, 10 a transformer primary included in said circuit arrangement by means of which variable currents may be supplied to another circuit, and a variable resistance connected between two points in said transformer primary which are at the same potential with respect to the direct current component of the source.

5. The combination in an amplifying system of a push-pull circuit arrangement 20 which includes a source of direct current and means for producing variable currents, a transformer primary included in said circuit arrangement by means of which variable currents may be supplied to another 25 circuit, and an adjustable impedance connected between the terminals of said transformer primary.

6. The combination in an amplifying sys-

tem of a push-pull circuit arrangement 30 which includes a source of direct current, and means for producing variable currents, a transformer primary included in said circuit arrangement by means of which variable currents may be supplied to another circuit, and a variable resistance connected 35 between the terminals of said transformer primary.

7. The combination in an amplifying system of a push-pull microphone, a circuit arrangement connected thereto which includes 40 a source of direct current and a transformer primary, and an impedance connected between two points in said transformer primary which are at the same potential with respect to the direct current component of 45 the source.

8. The combination in an amplifying system of a push-pull microphone, a circuit arrangement connected thereto which includes 50 a source of direct current and a transformer primary, and a variable resistance connected across the terminals of said transformer primary.

In witness whereof, I have hereunto set my hand this 30th day of October, 1924.

IRVING F. BYRNES.
